UNITED STATES PATENT OFFICE.

WILLIAM W. VOSEBURGH, OF TROY, NEW YORK.

TICKET-HOLDING DEVICE.

Application filed May 27, 1926. Serial No. 112,072.

This invention relates to the class of clasps and holding devices used for holding tickets and the like.

An object of the present invention is the provision of a ticket holder used upon the backs of seats of railway cars for releasably holding passenger tickets in a manner in which they will be conveniently accessible and held in sight.

Another object of the invention is the provision of a ticket holder or clasp which will be simple in construction, neat in appearance when attached and which will be comparatively inexpensive to produce.

The nature of the invention and its distinguishing features and advantages will appear when the following specification is read in connection with the accompanying drawing, in which—

Figure 1 is a sectional elevation in which a portion of a seat back is shown having the usual binding strip which is partly shown in section and to which the holding device of the present invention is attached, the device being shown in longitudinal section, and a ticket being held by the device.

Fig. 2 is a sectional view taken on the line 2—2 of Fig. 1.

Fig. 3 is a perspective view of one part of the device.

Fig. 4 is a perspective view of a part of the device which is used in conjunction with the part of the device shown in Fig. 3.

Referring now more particularly to the drawing, it will be apparent that as illustrated in the present instance a device 10 of the present invention is attached to the binding strip 11 of the back 12 of a seat; only a portion of the back and its strip being shown. The device 10 comprises two main parts, a part 13 and a part 14 which are maintained in association with each other by a means in the form of a single fastening element such as the screw 15. The part 14 is of integral construction and is formed with flanges 16 and an extension in the form of a finger 17 or gripping member on the body 18. The body 18 at the juncture of the finger 17 with the body 18 is formed with an abutment or shoulder 19. The body 18 is provided with a threaded hole 20. The part 14, in the present instance, is of integral construction made of spring metal stamped, bent and formed to provide a portion 21 having a hole 22 therein, a portion 23 disposed substantially at a right angle to

the portion 22, and a portion 24 which is narrower than the portion 21 and serves as a spring finger or gripping member.

To attach the device the two main parts 13 and 14 are brought together so that the portion 21 of the part 14 will be disposed beneath the body 18 in the recess between the flanges 16 and, with the portion 23 against the shoulder 19, and the spring finger 24 in coacting relation with respect to the finger 17. Under this arrangement the hole 22 in the portion 21 is in registration with the threaded hole 20. The screw 15 is extended through a hole in the binding strip 11, extends through the hole 22 and is threaded into the hole 20, thus securing the device in place on the top portion of the binding strip 11. This is done before the binding strip is secured in place on the back of the seat.

It will be apparent that the flanges 16 which embrace the sides of the binding strip prevent turning movement of the device when applied; that the part 13 is well rounded so that it will be neat in appearance and will eliminate all sharp corners, and that the extremities of the fingers 17 and 24 are rounded to facilitate the insertion of a ticket or the like between the fingers. To insert a ticket or the like 25 between the fingers 17 and 14 it is only necessary to push the same between the fingers; the abutment or shoulder 19 serving as a means for limiting the extent of insertion, thereby insuring the extension of a major portion of the ticket or the like in full view conveniently accessible at one side of the device 10 directly above the binding strip.

I claim:

1. The combination with the back of a seat having a binding strip, of a ticket holding device having a part formed to straddle the strip and a finger disposed parallel to the strip, above the strip and spaced therefrom, a second part arranged between the first mentioned part and the strip, the two parts held in place by a means which extends through the strip and second mentioned part and into the first mentioned part, the second mentioned part having a flexible finger which coacts with the finger on the first mentioned part to releasably hold a ticket.

2. The combination with the back of a seat having a binding strip, of a ticket holding device comprising two gripping members adapted to be brought together to lie

upon said strip substantially parallel thereto, one of said members having means embracing the opposite sides of the strip, and a screw extending from the strip, through 5 one end of one of the gripping members, and threaded into one end of the other gripping member.

3. The combination with a strip, of a ticket holding device comprising two gripping members, one of said gripping members 10

having means at one end straddling the strip, the other gripping member having an offset end arranged between the strip and said straddling means, and means extending from the strip, through said offset end and 15 into said straddling means for securing the gripping members in place in coacting relationship.

WILLIAM W. VOSBURGH.
